UNITED STATES PATENT OFFICE

171,290

REMOTELY CONTROLLED AIRPLANE

William B. Bergen, Glenarm, John Donald Rauth, Middle River, Leonard M. Michal, Essex, and Welcome W. Bender, Glenarm, Md., assignors to The Glenn L. Martin Company, Middle River, Md., a corporation of Maryland

Application November 25, 1949, Serial No. 6,238

Term of patent 14 years

(Cl. D71—1)

To all whom it may concern:

Be it known that we, William B. Bergen, John Donald Rauth, Leonard M. Michal, and Welcome W. Bender, citizens of the United States of America and residents, respectively of Glenarm, county of Baltimore, State of Maryland; Middle River, county of Baltimore, State of Maryland; Essex, county of Baltimore, State of Maryland, and Glenarm, county of Baltimore, State of Maryland, have invented a new, original, and ornamental Design for a Remotely Controlled Airplane, of which the following is a specification, reference being had to the accompanying drawings, forming a part thereof.

Figure 1 is a perspective view of the airplane taken from below.

Figure 2 is a top perspective view thereof, a portion having been broken away for convenience of illustration.

Figure 3 is a top plan view thereof.

Figure 4 is a front elevational view thereof.

Figure 5 is a side elevational view thereof.

We claim:

The ornamental design for a remotely controlled airplane, as shown.

WILLIAM B. BERGEN.
JOHN DONALD RAUTH.
LEONARD M. MICHAL.
WELCOME W. BENDER.
